UNITED STATES PATENT OFFICE.

WILLIAM GOODWIN POWELL, OF ALTOONA, PENNSYLVANIA.

SLIDE DOOR FOR BOX CARS.

Application filed March 1, 1926. Serial No. 91,588.

This invention relates to doors and particularly to metal side doors for use on box cars. The invention involves certain detailed improvements over the construction disclosed in my copending application Serial No. 725,653 filed July 12, 1924.

The present invention aims to provide an improved arrangement for securing the vertical stiffener bars to the front and rear edges of the door whereby the operation of assembling the door and stiffener bars is simplified and cheapened and the resulting construction rendered very strong and durable.

The invention and the numerous advantages thereof will be more fully understood from the following specification and the accompanying drawings, forming a part thereof, and in which:

Fig. 1 is a partial elevation of the side of a box car having a door constructed according to the present invention;

Fig. 2 is a horizontal section partly broken away, on the line 2—2 of Fig. 1;

Fig. 3 is a partial vertical section through one of the horizontal corrugations of the door and taken on line 3—3 of Fig. 1;

Fig. 4 is a partial sectional view similar to one end of Fig. 2 and showing a slightly modified arrangement; and

Fig. 5 is a horizontal section similar to Fig. 2 showing another modified arrangement.

Referring to the drawings by the reference characters thereon, 10 indicates part of a box car body to which the improved door, generally indicated by the numeral 11, is applied. The door may be slidably supported on the car in any suitable manner, as by pairs of rollers 12 adapted to travel on a track 13, the upper edge of the door being held in place by a bar 14 beneath which the door may slide.

As in the case of my said prior application, the door is preferably formed of a plurality of metal plates 11^A secured together at their meeting edges in such a way as to form horizontal ribs or corrugations 11^B extending across the door. These corrugations are produced by bending the edge portions 11^C of adjacent plates outwardly at substantially a right angle to the plane of the plates 11^A, and then bending the marginal portions 11^D of the plates into a plane substantially parallel to the plane of the plates. The portions 11^D are then over-

lapped and riveted together as at 11^E. There is thus produced a corrugation at the meeting edges of each two adjacent plates 11^A. That portion of the corrugations 11^B formed by the overlapping edges 11^D of the plates, will hereinafter be termed the top of the corrugations. In the present arrangement, the corrugations 11^B preferably extend inwardly instead of outwardly as in my said prior application.

Referring to Figs. 1, 2, 3 and 4, I arrange an angle member 15 adjacent the end of each corrugation. Each of these angle members has one of its legs 15^A riveted to the top of the corrugation. The leg 15^A may be, and preferably is, riveted to the inner surface of the top of the corrugation, as in Figs. 2 and 3, although it may if desired be riveted to the outer surface of the top as shown in Fig. 4. The outer leg 15^B of each angle member 15 extends transversely of the end of the corrugation and vertically extending stiffener bars 16 and 16' are riveted to each of said legs 15^B. The stiffener bar 16 is preferably provided with a flange 16^A which overlies and contacts with and is riveted to the plane surfaces of the plates 11^A between the corrugations 11^B. The stiffener bar at the front of the door is preferably in the form of a Z bar having a flange 16^B for co-operating with the door-post, as described in my former application, and the stiffener bar at the rear of the door is provided with a distorted flange 16^C, the purpose of which is also fully set forth in said prior application.

In the form illustrated in Fig. 5, the stiffener bars 20 and 20' are substantially the same as the bars 16 already described, and are provided with flanges 20^A, 20^B and 20^C which perform the same functions as the corresponding flanges 16^A, 16^B and 16^C. In this form, however, the bars 20 are provided with supplemental flanges 20^D, preferably integral therewith, and which extend the full length of the bars 20. The flanges 20^D overlie and are secured by riveting to the tops of the corrugations 11^B. The function of the planes 20^D is therefore analogous to that of the angle members 15.

The construction described provides a door which is comparatively light and cheap to manufacture and which is very strong and rigid and durable, and capable of withstanding the severe usage to which such doors are subjected in use.

Having thus described the invention, what is claimed as new and desired to be secured by Letters Patent is:

1. A metal door having a plurality of horizontal corrugations therein terminating at the edge of the door, an angle member arranged adjacent an end of each of said corrugations, each of said angle members having one leg riveted to the top of its respective corrugation, a vertical stiffener bar extending along the edge of the door and riveted to the other leg of each of said angle members.
2. A metal door having a plurality of horizontal corrugations therein, an angle member arranged adjacent an end of each of said corrugations, each of said angle members having one leg thereof riveted to the inner surface of the top of its respective corrugation and having its other leg extending transversely of the end of the corrugation, a vertical stiffener bar extending along the edge of the door and riveted to the last named legs of said angle members.
3. A metal door having a plurality of inwardly extending corrugations therein, an angle member arranged in each of said corrugations, each of said angle members having one leg secured to the top of the corrugation in which it is mounted and having its other leg extending outwardly, a vertical stiffener bar extending along an edge of the door and riveted to said outwardly extending legs of said angle members.
4. A metal door having a plurality of horizontal corrugations therein and flat portions between said corrugations, an angle member arranged at an end of each of said corrugations, one leg of each of said angle members being secured to the top of its respective corrugation and the other leg extending transversely of the end of the corrugation, a vertical stiffener bar extending along the edge of the door and secured to the last named legs of said angle members, said bar having a flange overlapping and secured to the said flat portions of the door.
5. A metal door formed of a plurality of horizontal panels having their meeting edges riveted together, said meeting edges of the panels being bent out of the plane of the panels to form a plurality of horizontal corrugations, an angle member arranged adjacent an end of each of said corrugations, each of said angle members having one leg secured to the top of the corrugation adjacent which it is mounted and having the other leg extending outwardly toward the plane of the panels, a vertical stiffener bar extending along the edge of the door and secured to the last named legs of said angle members, said bar having a flange overlapping and secured to said panels between said corrugations.
6. A metal door formed of a plurality of horizontal panels, the meeting edges of said panels being bent inwardly and secured together to form a plurality of inwardly extending corrugations in the door, an angle member arranged in each of said corrugations, each of said angle members having one leg thereof secured to the inner surface of the top of the corrugation in which it is mounted and the other leg extending transversely of the end of the corrugation, a vertical stiffener bar extending along the edge of the door and secured to the last named legs of said angle members, said bar having a flange overlying and secured to said panels between said corrugations.
7. A metal door having a plurality of corrugations extending transversely thereof, an angle member arranged in an end of each of said corrugations, one leg of each of said angle members being secured to the corrugation in which it is mounted and the other leg of each of said angle members extending transversely of the corrugation in which it is mounted, a stiffener bar extending along the edge of the door and riveted to the last named legs of said angle members.

In testimony whereof I hereunto affix my signature.

WILLIAM GOODWIN POWELL.
